UNITED STATES PATENT OFFICE.

JOHN H. COWAN, OF KANSAS CITY, MISSOURI, ASSIGNOR TO THE COWAN HAIR CUTTER COMPANY, OF KANSAS CITY, MISSOURI, A CORPORATION OF MISSOURI.

COMBINATION HAIR TRIMMER AND SAFETY RAZOR.

Application filed December 26, 1919. Serial No. 347,340.

To all whom it may concern:

Be it known that I, JOHN H. COWAN, a citizen of the United States, residing at Kansas City, in the county of Jackson and State of Missouri, have invented a new and useful Improvement in Combination Hair Trimmers and Safety Razors, of which the following is a specification.

This invention relates particularly to a device adapted to be used either as a hair-cutter or as a safety-razor; and the primary object is to provide an improved device of this character which is thoroughly durable, which can be taken apart and assembled with the greatest facility, and which is of improved operation.

The invention is illustrated, in its preferred embodiment, in the accompanying drawing, in which—

Fig. 1 represents a plan view of the improved device, looking toward the outer face of the shoe employed, an oblique position of the comb-plate being indicated by dotted lines; Fig. 2, an elevational view of the device, adjusted for use as a safety-razor; Fig. 3, an under or inner side view of the shoe; Fig. 4, a plan view of the blade; Fig. 5, an outer or lower side view of the comb-plate; Fig. 6, a broken sectional view taken as indicated at line 6 of Fig. 1, showing the device equipped with a handle applied at one end, enabling the device to be employed in much the manner of an old-fashioned razor; and Fig. 7, an enlarged sectional view showing the device ready for use as a hair-trimmer.

In the illustration given, A represents a shoe which is adapted to make contact with the face or head; B, a blade which bears against the under or inner side of the shoe; C, a comb-plate which is adapted to clamp the blade to the shoe; D, a clamping-screw adapted to secure the comb-plate and the interposed blade to the shoe; and E, an elongated handle which can be used interchangeably at the ends of the shoe, or in the manner illustrated in Fig. 2.

The shoe A is provided with an inclined wall 1 which is elongated longitudinally so as to be of approximately the same length as the blade. This wall terminates at its front edge in a reduced toe 2, and the rear portion of the wall is provided with an integral heel 3. The heel and toe portions of the shoe are separated by a longitudinal

space 4. The lower or inner surfaces of the toe and heel portions of the shoe are preferably curved, or beveled, slightly so as to provide longitudinal bearings for the blade at the points 5 and 6. The shoe may comprise a casting or drop-forging. The heel-portion 3 is in the shape of a longitudinal ledge, or projection, which is provided with a central threaded socket 3^a and with interlock lugs 3^b which flank said socket. At its front side, the heel-portion is cut away, or recessed, at points 3^c, these recesses opening into the recess 4 under the instep of the shoe. These recesses lighten the shoe. At the rear corner of the heel, there is provided a longitudinal recess 7 which is adapted to accommodate a rear flange with which the comb is provided, when the comb is in the forwardly shifted position. At the end of the heel-portion of the shoe are provided threaded sockets 8 adapted to receive a screw of the same dimensions as the central socket 3^a. The shoe is provided with a longitudinal recess 9 which is partially overhung by the rear portion of the wall 1. The heel is provided at its rear side with a projection which affords a curved shoulder 10. The recess 9 has a concave wall, the curve of which is extended and merged with the convex surface 10. Thus, the rear portion of the shoe affords a finger-grip, which enables the device to be grasped between the fingers and thumb, the thumb engaging the head of the clamping-screw D.

The blade B is provided with a central perforation 11 and with slots, or perforations, 12, flanking the central perforation and adapted to engage the interlock lugs 3^b of the shoe.

The comb-plate C is provided at its front edge with teeth 13 and preferably has its rear edge equipped with a longitudinal flange 14, which is adapted to be housed in the recess 7 of the shoe when the comb-plate is projected forwardly to the full extent. The comb-plate is provided with a central slot 15 which extends forwardly from a point near the rear edge of the comb-plate. The metal bordering this slot is preferably struck downwardly or away from the shoe, to provide a bead, or strengthening rib, 15^a. At points flanking the central slot, the comb-plate is provided with slots 16, which engage the interlock lugs 3^b. The slots 16 are somewhat wider than the length 110

of the interlock lugs 3^b, thus permitting the comb-plate to be swung to an oblique position, as indicated by dotted lines in Fig. 1. The purpose is to graduate the length of the hair in the trimming operation.

The clamping-screw D has a reduced threaded perforation which screws into the socket 3^a, and also has an enlarged head 17, at the base of which is a shoulder 17^a adapted to bear against the bead 15^a bordering the center slot 15 of the comb-plate. Thus the clamping-screw is adapted to clamp the comb-plate and the interposed blade to the shoe. The enlarged head 17 of the clamping-screw is provided with a curve 17^c of comparatively large radius, which enables the thumb to grasp the screw in opposition to the fingers which engage the finger-grip of the shoe. It is preferred to provide the outer end of the clamping-screw with a threaded socket 17^b of the same dimensions and pitch as the sockets 3^a and 8.

The handle E is in the form of a shaft 18, which is equipped at its inner end with a reduced threaded portion, or screw, 18^a, which is adapted to screw into any one of the sockets mentioned. The handle is also provided with a clamping shoulder 18^b.

The manner of using the improved device may be described briefly. With the parts assembled as shown in Fig. 7, the device may be employed for cutting or trimming the hair; and, if desired, the comb-plate may be adjusted to an oblique position, so that the ends of the teeth will coincide with an inclined line forming an angle with the cutting edge of the blade. Thus, the teeth will project successively further and further from the edge of the blade. This enables the hair to be trimmed closer at the edges than could be accomplished were the teeth all to project the same distance from the edge of the blade.

By retracting the comb-plate, or moving it rearwardly with relation to the shoe and blade, the comb-plate may be set so as to enable the device to be employed as a safety-razor. When the proper adjustment is made, the device can be employed either in the condition shown in Fig. 7, or the handle E may be applied and the device employed in the condition shown in Fig. 2. However, if desired, the handle E may be applied to the shoe at either end thereof by turning the screw-portion 18^a of the handle into one of the sockets 8. In this condition, the device may be employed very much as an ordinary razor is employed. While the handle E is shown in Fig. 2 as screwed into the clamping-screw D, it is possible to remove

the screw D and use the handle E as the clamping-screw for securing the comb-plate and blade to the shoe.

The improved device may be manufactured at moderate cost, may be assembled and disassembled with facility, and may be converted to suit the user, who may employ either the short handle D, or the longer handle E, or both, and the longer handle E may be disposed at right-angles to the plane of the comb-plate, or extending from either end of the shoe, as desired.

The foregoing detailed description has been given for clearness of understanding only, and no unnecessary limitation should be understood therefrom, but the appended claims should be construed as broadly as permissible, in view of the prior art.

What I regard as new and desire to secure by Letters Patent, is:

1. A device of the character set forth, comprising a shoe having its inner side adapted to bear against a blade, said shoe having an inclined outer surface meeting the plane of the blade and having its rear portion equipped with a finger-grip, a blade bearing against the inner side of said shoe, a comb-plate between which and said shoe said blade is interposed, and a clamping screw securing said comb-plate and blade to the rear portion of said shoe, said clamping screw being adapted to serve as a thumb-piece, whereby the device may be grasped between the thumb and fingers.

2. A device of the character set forth, comprising a shoe having one side adapted to engage a blade and provided with a longitudinal recess and having an inclined surface at the other side, a comb-plate provided with a central slot and two widened slots flanking the same, a blade interposed between the shoe and comb-plate, and a clamping screw extending through said slot and engaging a threaded central socket in the heel-portion of said shoe.

3. A device of the character set forth, comprising a shoe having an inclined wall terminating at its front edge in a toe, the rear portion of said wall having formed integrally therewith a ledge affording a heel, said heel having a longitudinal recess at its rear inner corner, a comb-plate having a central slot and having a rear flange adapted to engage said recess, a blade interposed between said comb-plate and said shoe, and a clamping screw extending through said comb-plate and engaging a central threaded socket in said heel.

JOHN H. COWAN.
